CENTRIFUGAL PUMP

Anatol J. Harlamoff, South Gate, Calif., assignor
to A. O. Smith Corporation, Milwaukee, Wis., a
corporation of New York

Application October 6, 1945, Serial No. 620,780

3 Claims. (Cl. 103—87)

1

This invention relates to a centrifugal pump and is particularly directed to an in-line motor-pump unit.

The principal object of the invention is to provide a centrifugal pump with a double volute construction adjacent the impeller that simplifies casting of the pump.

Another object is to provide a simplified construction of a pump that effects increased efficiency.

A further object is to provide a novel construction for handling the discharge of an impeller of an in-line motor driven pump.

Another object is to provide a plurality of longitudinal ducts around the motor and leading from the volutes to the discharge end of the pump.

In carrying out the invention the diffuser and vanes ordinarily employed in previous constructions are completely eliminated and instead a double volute connects the impeller with a plurality of discharge passages that extend throughout the length of the pump and around the motor portion of the pump.

The invention is illustrated in the accompanying drawings, in which:

Figure 1 is a longitudinal central section of a pump illustrating an embodiment of the invention;

Fig. 2 is a transverse section taken on line 2—2 of Figure 1;

Fig. 3 is a transverse section taken on line 3—3 of Figure 1;

Figure 4 is a section broken out of the pump and showing the curvature of one of the volutes and separation thereof into two longitudinal passages; and

Fig. 5 is a section taken on line 5—5 of Figure 1 across the inner end of the discharge nozzle.

The invention is illustrated as employed with a centrifugal pump comprising a generally cylindrical cast housing 1 with the suction nozzle 2 secured to the forward end thereof and the discharge nozzle 3 secured to the rear end thereof.

The motor 4 is suitably secured within the body portion of the housing 1 in a motor chamber provided by the inwardly extending flange 5 adjacent the forward end of the housing 1 and the inwardly extending flange 6 adjacent the rear end of housing 1.

The forward radial bearings 7 are secured to web 8 extending inwardly from flange 5 and the rear radial bearings 9 are secured to flange 6. The shaft 10 of motor 4 is mounted within bearings 7 and 9 for free rotation thereof by motor 4.

The impeller 11 is mounted on the forward end of shaft 10 within a generally large axial pump chamber formed between the nozzle 2 and the flange 5 of housing 1. The impeller 11 together with the suction nozzle 2 providing the suction passage to the impeller, the forward wear ring 60

2

12, rear wear ring 13, the forward thrust bearing 14, and rear thrust bearing 15 comprise the pump portion of the centrifugal pump described.

The flange 5 extends inwardly substantially to shaft 10 and is sealed thereagainst to separate the motor and pump chambers by the cylindrical bushing 16 mounted on the shaft and constituting a wear ring in cooperation with the rear wear ring 13 on flange 5. The bushing sleeve 16 also extends within the radial bearing 7 to support the shaft therein. The forward end of bushing 16 provides a bearing plate for rear thrust bearing 15.

The head of bushing 16 is confined between the shoulder 17 on shaft 10 and the rotating ring member of rear thrust bearing 15 disposed between the bushing and the impeller 11.

The stationary member of the forward thrust bearing 14 is threaded into the housing 1 and is also supported axially against nozzle 2. The stationary member of forward wear ring 12 is secured to nozzle 2 and the rotating member thereof is carried by the front shroud of impeller 11.

A by-pass 18 through forward thrust bearing 14 connects with a passage 19 in nozzle 2 and permits pumped fluid from the discharge side of the impeller to flow through forward wear ring 12 to axial clearance passage 20 and thence to the suction inlet of nozzle 2. This improves the balance of the impeller and lubricates the wear ring.

30 A portion of the circulating fluid flows through the motor chamber to cool the motor by means of orifice 21 in discharge nozzle 3 and orifice 22 in housing 1 adjacent the forward flange 5. The by-pass 23 connects orifice 22 in housing 1 with the suction nozzle 2. The orifices limit the flow of fluid through the motor chamber.

The housing 1 is provided with four separate longitudinal discharge passages 24, 25, 26, and 27 by casting the housing with a double wall at circumferentially spaced intervals. The inner circumferential walls 28 of the corresponding passages form a housing for the motor 4 and radially locate the stator of the motor 4 within the body portion of housing 1. The passages 24, 25, 26, and 27 with their respective inner walls 28 extend substantially the length of the motor chamber.

Also in the casting operation the housing 1 is provided at the forward end portion with a double volute construction comprising the upper volute 29 and the lower volute 30 as illustrated in Fig. 2 of the drawings. The volutes 29 and 30 register with the discharge of the impeller at substantially diametrically opposite sides of impeller 11.

The volute 29 terminates in passage 31 which is separated by the hollow rib 32 into the passages 24 and 25 above described. The hollow rib 32 is also formed as a part of housing 1 in the casting operation.

The lower volute 30 terminates in a passage

similar to passage 31 and which is separated by the hollow rib 33 to connect with discharge passages 26 and 27 above described. The hollow rib 33 is similar to rib 32 and is formed as a part of housing 1 in the casting operations. The ribs 32 and 33 constitute parts of the walls of passages 24, 25, 26 and 27 extending for substantially the length of the housing at opposite sides thereof and are closed at opposite ends at generally sharp separation points.

The longitudinal passages 24, 25, 26 and 27 of housing 1 register with four similar passages 34 in the discharge nozzle 3. Passages 34 gradually merge into the circular discharge passages 35 at the flanged outlet of nozzle 3.

A generally short radial rib 36 is also cast integral with housing 1 and is disposed in hollow rib 32 between housing 1 and the stator of motor 4. A key 37 secures the motor stator to rib 36 to prevent rotation of the stator in service. Dog point screw 38 extends through the enlarged end of rib 36 to additionally secure the stator of motor 4 and prevent axial movement thereof.

The motor 4 is circumferentially held by the cast inner walls 28 of housing 1 through which extend discharge passages 24, 25, 26 and 27. Fluid pumped through the discharge passages effectively cools the motor by conduction of heat from the stator thereof through the walls 28.

Fig. 4 illustrates volute 29, passage 31, and passages 24 and 25 in detail. Passages 26 and 27 handling the discharge through lower volute 30 and the connecting passage therebetween are not shown in detail since the construction is similar to Fig. 4. Fig. 3 illustrates all four of the passages through housing 1 and Fig. 5 shows the four passages 34 of the discharge nozzle 3.

Hollow ribs 32 and 33 may be eliminated to provide only two longitudinal passages through housing 1. The passages may also be increased in number by subdividing each of passages 24, 25, 26 and 27.

The electrical connections for the motor may be made through one of the hollow ribs 32 as shown in Fig. 3.

The in-line type of centrifugal pump construction of the present invention provides a strongly supported housing for the motor while utilizing the supports therefor as discharge passages and as passages through which pumped fluid passes to cool the motor.

By providing a double volute discharge for the impeller and conducting the pumped liquid from these volutes through separated passages along the motor chamber to the discharge end of the pump, the casting of the housing is simplified and the efficiency of the pump is increased over that of prior constructions.

In earlier constructions it was difficult to turn the discharge flow from the impeller to a longitudinal direction along the motor and at the same time spread the flow so that it substantially enclosed the motor on all sides for cooling the same, without reducing the efficiency of the impeller by reason of resistance to the discharge of liquid therefrom.

Various embodiments of the invention may be employed within the scope of the accompanying claims.

I claim:

1. In an in-line centrifugal pump of the class described, a shaft, an impeller and a motor,

said shaft being common to the impeller and the motor, a dual-walled housing surrounding said impeller and motor in radially spaced relation to the latter and having an inlet for the impeller at one end and an outlet for discharge of pumped fluid at the opposite end, and a series of circumferentially spaced longitudinally extending passages disposed between the inner and outer walls of the housing to conduct pumped fluid from the impeller to said discharge outlet in substantial heat conductive relation to the inner wall of said housing to effect cooling of the motor, the walls of said passages being exposed on three sides to direct heat conductive relation with the fluid medium surrounding the motor inside the housing and in said radial space between the motor and housing.

2. In an in-line centrifugal pump of the class described, a shaft, an impeller and a motor, said shaft being common to the impeller and the motor, a dual-walled housing surrounding said impeller and motor in radially spaced relation to the latter and having an inlet for the impeller at one end and an outlet for discharge of pumped fluid at the opposite end, a series of circumferentially spaced longitudinally extending passages disposed between the inner and outer walls of the housing to conduct fluid from the impeller to said discharge outlet in substantial heat conductive relation to the inside wall of said housing to effect cooling of the motor, and electrical connections for the motor passing through the housing in the space between two passages to avoid interference with the pumped fluid flowing through the passages.

3. In an in-line centrifugal pump of the class described, a shaft, an impeller and a motor, said shaft being common to the impeller and the motor, a dual-walled housing surrounding said impeller and motor in radially spaced relation to the latter and having an inlet for the impeller at one end and an outlet for discharge of pumped fluid at the opposite end, a series of circumferentially spaced longitudinally extending passages disposed between the inner and outer walls of the housing to conduct fluid from the impeller to said discharge outlet in substantial heat conductive relation to the inside wall of said housing to effect cooling of the motor, and bleeder connections for the inside of said housing with said inlet and outlet to provide for controlled reverse circulation of pumped fluid through the housing around the motor and in contact with the walls of said passages.

ANATOL J. HARLAMOFF.
